UNITED STATES PATENT OFFICE.

GEORGE W. NOYES, OF BILLINGS, MONTANA.

FILM-GUIDING DEVICE.

Application filed September 15, 1920. Serial No. 410,363.

To all whom it may concern:

Be it known that I, GEORGE W. NOYES, a citizen of the United States, residing at Billings, in the county of Yellowstone and State of Montana, have invented a new and useful Film-Guiding Device, of which the following is a specification.

This invention relates to a film holding and guiding device and more particularly to 10 a device of this character especially designed for facilitating the lining up of one film strip with another film strip when film strips are to be spliced, to insure against misframing of the pictures, when the same 15 are projected.

Another object of the invention is to provide a device to be moved over a film strip, to the device having markings thereon, to align with the lower edges of the pictures 20 of the film strip, so that when the device is moved over the film strip and over the fade-out portion thereof, the markings will indicate where the strip to be spliced should be positioned to cause the pictures thereof to 25 frame when passed through the projecting machine.

A further object of the invention is to provide a device of this character including teeth adapted to move in the perforations 30 at the edges of a moving picture film strip to insure against lateral movement of the film strip while being positioned preparatory to the splicing thereof.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed, may be made within the scope of what is claimed, without departing from the spirit of the invention.

Referring to the drawings:—

45 Figure 1 illustrates a side elevational view partly in section, of a device constructed in accordance with the present invention.

Figure 2 is an end elevational view; and

50 Figure 3 is a transverse sectional view showing the cooperation between the device and the film strips under operation.

Referring to the drawings in detail, the device includes a pair of arms 5 and 6 respectively, which arms are pivotally connected through the medium of the apertured

ears 7 forming a part of the arm 5, and the pivot pin 8, forming a part of the arm 6.

This arm 6 has an angularly disposed handle portion, and a relatively straight jaw section 9 which cooperates with the jaw section 10 to support the rollers 11 and 12, there being provided a coiled spring 13 having connection with each of the jaws, for normally urging the jaws towards each other to cause the rollers 11 and 12 to closely engage each other, with the result that the film passing between the rollers is pressed into close engagement therewith.

A shaft indicated at 14 forms a part of each of the jaws 9 and 10, and on these 70 shafts are mounted the rollers 11 and 12, securing nuts 15 being provided to secure the rollers 11 and 12 against displacement longitudinally of the shafts 14, when the device is in operation.

The roller 11 includes a central hub and enlarged end portions 16, which end portions include circumferential flanges 17 between which the film under operation moves, the distance between the flanges being equal 80 to the width of the film to insure against a film moving laterally from the rollers.

Formed on each of the enlargements 16 are a plurality of teeth or pins 18 which teeth are designed to operate in the openings 85 formed laterally of a film, so that when the device is moved over the film the roller will revolve over the film strip. The cooperating roller 12 is relatively small, as compared with the roller 11, and is provided with circumferential grooves 19 adjacent the ends thereof, which grooves accommodate the pins 18, permitting the pins to pass through the openings of the film.

Adjacent each end of the roller 12 is a 90 disk 20 which disks operate over the surfaces of the enlarged portions 16 of the roller 11, and press the film into engagement with the enlarged portions 16.

In splicing moving picture film, it is absolutely necessary that the pictures of the film register in order that they will be properly framed when passed through a moving picture machine, and to this end markings 21 are provided at predetermined points on the roller 11, the distance between the markings representing the distance between the upper and lower edges of a picture. In the use of the device, if it is desired to splice 105 a film strip to the fade-out end of another 110

- film strip, the device is placed on that portion of the film strip where the pictures are visible, so that the lower edge of a picture will align with one of the markings 21 of the flanges 17. The device is now moved over the film strip towards the fade-out end thereof, and when the markings 21 of the roller 11 have moved to indicate the point where the last picture of the film would fall, the upper edge of a picture at the end of the film strip to be spliced, is brought into alignment with the marking of roller 11 which now falls adjacent to the fade-out end of the film strip.
15. With the strips in this position, they may be secured together in the usual and well known manner.

Having thus described the invention, what is claimed as new is:—

20. 1. In a device of the character described, a pair of pivotally connected arms, said arms including handle portions, a roller carried at one end of each arm, said rollers adapt-

ed to cooperate to clamp a film therebetween, one of said rollers having teeth to engage within openings of a moving picture film, and means for normally urging the rollers towards each other.

2. In a device of the character described, a pair of pivotally connected arms, each of said arms including a jaw, a shaft forming a part of each jaw, a roller rotatably mounted on the shaft, one of said rollers having an enlargement at each end thereof, a flange forming a part of each enlargement, the opposite roller operating between the flanges for forcing a film into engagement with the enlargement, and means for normally urging the rollers towards each other.

In testimony that I claim the foregoing as my own, I have hereto affixed my signature in the presence of two witnesses.

GEORGE W. NOYES.

Witnesses:

H. C. ROTHWELL,
KIRKE NOYES.
